UNITED STATES PATENT OFFICE.

BENNETT SONBERG, OF NEW YORK, N. Y.

DESIGN FOR A FERN-DISH HANGER.

49,402.

Specification for Design.

Patented July 18, 1916.

Application filed December 21, 1915. Serial No. 68,098. Term of patent 7 years.

To all whom it may concern:

Be it known that I, BENNETT SONBERG, a citizen of the United States, residing at 947 Sherman avenue, in the city of New York, county of Bronx, and State of New York, have invented a new, original, and ornamental Design for Fern-Dish Hangers, of which the following is a specification, reference being had to the accompanying drawing, forming part thereof.

I claim:

The ornamental design for a fern dish hanger, as shown.

BENNETT SONBERG.
